Company, Milwaukee, Wis., a corporation of
Wisconsin

Application May 28, 1945, Serial No. 596,300

3 Claims. (Cl. 175—341)

1

This invention relates to electro magnetic attracting and holding apparatus dependent upon permanent magnetism for the holding action thereof. The invention resides more specifically in an improved form of apparatuses of this type in which a permanently magnetizable core portion is so disposed, intermediate the ends of a magnetizing coil, as to be subjected as nearly as possible to the full magnetizing force of which said magnetizing coil is capable.

Electro magnets arranged for the operation and control of electric switches such as relays have been constructed in a wide variety of forms including magnets which remain closed due to permanent magnetism. Such magnetic "latching" has several advantages, but in order to establish a permanent magnetism holding force of sufficient strength and dependability it has heretofore been necessary to apply a magnetizing force largely in excess of that which is appropriate for the mere attracting of the armature. As a result, excessive pounding and wear of mechanical as well as electrical parts has been encountered.

A further disadvantage of magnets heretofore available has been the tendency thereof to close when unduly low voltage is applied and then on termination of such deficient voltage to drop open again instead of remaining latched. Through the use of the apparatus of this invention the shortcomings of magnets of this type previously known is overcome. The magnet of this invention is easily permanently magnetized by a magnetizing force not materially greater than that appropriate for pick up and closing. In this way undue pounding and wear may be avoided. Furthermore, any applied voltage sufficient to cause pick up and closing also is adequate to establish sufficient permanent magnetism to insure the retaining of the magnet in closed position.

This invention is herein described by reference to the accompanying drawings forming a part hereof and in which there is set forth by way of illustration and not of limitation one form in which the apparatus of this invention may be embodied.

In the drawings:

Fig. 1 is a side view in elevation of a relay embodying a magnet constructed in accordance with this invention;

Fig. 2 is a top plan view of the relay shown in Fig. 1 with the upper contact cover removed to expose the contacts;

Fig. 3 is a bottom plan view of the relay shown in Fig. 1 with the bottom contact cover removed;

Fig. 4 is a side elevation in section of the relay shown in Fig. 1 viewed through the plane 4—4 indicated in Fig. 2;

Fig. 5 is a front view in elevation and in section

of the relay shown in Fig. 1 viewed through the plane 5—5 there indicated; and

Fig. 6 is a diagram of one form of circuit which may be employed with the apparatus shown in the preceding figures.

Referring now to the drawings the magnet of this invention is there shown associated with parts adapted to form an electric relay, for which use the magnet is particularly well adapted. As appears more clearly in Figs. 4 and 5 a magnet frame 1 of rectangular U-shaped form is secured by rivets to a mounting bracket 2, thus forming not only a magnet frame but also a supporting frame work for the entire relay. The upper ends 10 of the upwardly facing prongs of the U-shaped frame 1 are provided with bent back ears 3 to provide means for firm attachment through screws 4 with a top frame plate 5. In this way a rectangular, open sided magnet frame is formed composed of magnetic material of comparatively high magnetic permeability and low retentivity.

Permanently secured in a centrally disposed hole in the upper plate 5 is a downwardly extending upper core member 6 held in place by a peened rim 7. The upper core member 6 is composed of magnetic material of high permeability and low retentivity and is provided with an accurately machined lower face 8. Disposed beneath and spaced from the upper core member 6 is a lower core member 9 formed of similar material, the upper face 10 of which is also accurately machined. Disposed between and in intimate engagement with the faces 8 and 10 and there rigidly held by the tubular rivet 11 is an intermediate core member 12.

The intermediate core member 12 is composed of a magnetic material of exceptionally high retentivity and coercive force. Particularly well adapted for the construction of the intermediate core member 12 are the alloys of iron, aluminum and nickel or cobalt of the general class commonly called "Alnico." However, any material exhibiting the property of retaining permanent magnetism to a high degree may be employed and for this reason a successful practicing of this invention is not dependent upon the selection of the particular alloy or alloys above mentioned for the intermediate core member 12.

The parts above described constitute the entire stationary frame of the magnet and with these parts a coil 13 is associated in a particular manner so as to produce the specific magnetizing action required. As may be observed in Figs. 4 and 5 the coil 13 surrounds the upper and lower core members 6 and 9 and not only surrounds the intermediate core member 12 but extends a very substantial distance beyond the same both above and below it. By reason of this construction the flux created upon the energization of coil 13 is

substantially all compelled to thread the intermediate core member 12 by reason of its location at or in the near vicinity of the eye of the coil 13. Coil 13 may comprise if desired two separate windings as is set forth in Fig. 6, in which winding 13a is a closing or magnetizing winding and 13b is an opening or demagnetization winding which creates a flux of opposite polarity to that of winding 13a.

Immediately below the core member 9 a large circular opening 14 is formed in the lower horizontal part of the frame member 1. Disposed to move to and from the positions shown in Figs. 4 and 5, within the opening 14, is a collar shaped armature 15 having a vertical sleeve portion 16 and a seating rim 17. As appears in Fig. 4 the seating rim 17 is arranged to come into sealing engagement with the bottom face of frame member 1 while a small air gap is retained between the upper end of the sleeve 16 and the lower face of the lower core member 9.

Armature 15 is mounted upon and guided in its movement by a non-magnetic guide rod 18, received with a close but nevertheless freely sliding fit within the bore of tubular rivet 11. To form an engaging seat between the armature 15 and the rod 18 a boss 19, riveted in place within the armature 15 as shown, is bored to be closely received upon the reduced diameter portion 20 of the rod 18. The armature 15 is held in place against a shoulder on rod 18 formed by a reduced diameter portion 20 by means of a pre-loaded spring 21 interposed between the armature 15 and a lower insulating movable contact carrier 22 held in place by a C washer 23 which engages a groove in the end of rod 18. To augment the opening force due to gravity and to render the magnet operative in inverted position an opening compression spring 24 received within the recesses in lower core member 9 and armature 15 and interposed between these two parts is provided.

A closely fitting non-magnetic metallic sleeve 25 surrounds the core members 6, 9 and 12 to hold the coil 13 against lateral displacement while endwise displacement of coil 13 is restrained in the usual manner by means of a resilient bent washer 26.

Secured to the upper frame member 5 is an insulating stationary contact support 27 held in place by screws 21. Mounted upon contact support 27 is a pair of closed-position stationary load contacts and terminals 28 and an oppositely disposed pair of open-position stationary load contacts and terminals 29. Also mounted upon the contact support 27 is a pair of stationary closed-position pilot contacts and terminals 30 as well as a pair of open-position pilot contacts and terminals 31.

Mounted upon the upper end of the actuating rod 18 and there held between a C washer 32, engaging a groove in the upper end of rod 18, and a spring 33 engaging a shoulder 34, is an insulating movable contact carrier 35. The movable contact carrier 35 is so disposed as to carry movable bridging contacts 36 and 37 between load contacts 28 and 29 and to carry bridging contacts 38 and 39 to and from pilot contacts 30 and 31. Secured to posts 40 and 41 by means of sleeve nuts 42 and 43 is an upper contact cover 44.

Mounted on the lower face of frame member 1 by means of brackets 45 and screws 46 is a lower stationary contact support 47 composed of insulating material. Carried by the support 47 are stationary load contacts and terminals 48

and 49 in position to be engaged by movable bridging contacts 50 and 51 carried upon movable insulating contact carrier 22. Stationary cross connecting contacts 52 serve to complete a load circuit from terminal 48 to terminal 49 when the switch is in closed position. A lower contact cover 53 positioned as shown is held in place by sleeve nuts 54 and 55 which engage threaded supporting posts 56 and 57 which in turn are secured to the contact support 47 by riveting.

Binding posts 58, 59, 60, 61, 62 and 63 serve to provide connection with the windings 13a and 13b of coil 13 and the pilot contacts 30 and 31 and with a control circuit as shown in Fig. 6 for energization of the magnet to cause the same to close and open.

As shown in Fig. 6 direct current supply main 64 of positive polarity is connected by lead 66 with a normally open start push button 67 which is joined by a lead 68 with terminal 59 and one of the two stationary pilot contacts 30. Movable pilot contact 38 which is normally closed engages the other stationary pilot contact 30 which is joined through lead 69 and terminal 58 with closing winding 13a. The opposite end of closing winding 13a is joined through terminal 66 and lead 70 with the negative power main 65. Winding 13a is of appropriate resistance and number of turns to cause closing of the magnet 30 and permanent magnetization thereof.

For opening main 65 is joined by lead 17 normally open stop push button 72, lead 73, terminal 62, contacts 31 and 39 and lead 74 with terminal 61 at one end of winding 13b. The opposite end of winding 13b is joined through terminal 63 and lead 75 with positive power main 64. With the magnet in closed position, closure of stop button 72 completes a circuit for the creation of reverse flux in winding 13b of a reduced magnitude limited by resistance 76 which may be either a distributed internal resistance in the winding 13b or an external resistance as shown. Such limited reverse flux serves to demagnetize the hard core portion 12 to cause the magnet to open. Numerous forms of such circuits may be employed to accomplish the result desired including circuits which have but a single winding in coil 13 with external resistance arranged to be introduced when reverse polarity opening current is applied.

Upon excitation of coil 13 for closing, the flux prevailing in the magnetic circuit begins to build up but movement of armature 15 does not take place initially because of substantial leakage of flux from the lower face of core member 9 to the lower horizontal portion of frame 1 without passing through the armature 15. As flux further increases, a substantially larger portion thereof begins to pass from the lower face of core member 9 to the armature 15 and thence to the frame 1. When the flux passing through the armature 15 reaches a value sufficient to create an attractive force capable of overcoming the action of spring 24 and other resisting forces, the armature 15 starts to move. By the time such movement starts to take place flux has been built up to a very substantial value, sufficient to establish considerable permanent magnetism in the intermediate core member 12. As movement of armature 15 progresses, the leakage of flux directly from the lower face of core member 9 to frame 1, is very rapidly diminished, until substantially all of the flux passes through the armature 15 in reaching the frame 1.

During the closing action the flux in the magnetic circuit approaches a maximum as the armature 15 approaches closed position. At this stage of the operation substantially all of the flux created by the coil 13 is compelled to pass through the intermediate member 12 thus insuring the maximum magnetization of this part which may be achieved with the magnetizing force available. If the hard, permanently magnetizable part 12 were embodied in the armature 15 or in the upper end of core member 6, it may be seen that a substantial amount of flux could pass from the core member to the frame member 1 or to the upper plate 5 without passing through the part to be permanently magnetized. This action would be further encouraged by the fact that alloys suitable for permanent magnet use do not have the highest possible permeability.

By reason of the relationship of the parts of the apparatus of this invention a certain definite minimum excitation of coil 13 is necessary to cause pick up of the armature. Any excitation exceeding such minimum will cause the armature 15 to close and close positively and at the same time will insure the magnetization of intermediate core member 12 sufficiently to insure the retention of the magnet in closed position. It is not necessary to excite the coil 13 to any degree in excess of that necessary to cause the picking up of armature 15 in order to create the necessary permanent magnetism to retain the magnet in closed position and therefore the magnet of this invention may be operated without unnecessary mechanical wear and tear and with the full assurance that closing will be positive and reliable.

We claim as our invention:

1. In an electrically controlled permanent magnet the combination comprising a central magnetic core having a relatively short medial portion composed of permanently magnetizable material exhibiting high coercive force and high retentivity and relatively longer end portions of magnetic material of high permeability disposed on opposite sides of said medial portion and in contact therewith, said short medial portion extending entirely across and completely separating said end portions; windings surrounding said core and extending lengthwise thereof beyond said medial portion on both sides thereof; a magnetic frame member surrounding said core and said windings having a magnetic top end plate secured to the top end of said core, a pair of magnetic side legs secured to said top end plate extending downwardly outside of said windings, and a magnetic lower end plate secured to said side legs in perpendicular relationship to said core, spaced from and extending across the free end of said core; said lower end plate being provided with an aperture disposed opposite the free end of said core, said aperture being completely surrounded on all sides by the magnetic material of said lower end plate; a movable armature of magnetic material disposed near the free end of said core in position to be attracted from open position to closed position with respect thereto, having a shank portion freely movable within said aperture, and a sealing flange adapted to contact the lower surface of said end plate adjacent to said aperture when said armature is in closed position; and an opening spring disposed between said armature and core adapted to urge said armature to open position.

2. In an electrically controlled permanent

magnet the combination comprising a central magnetic core having a relatively short medial portion composed of permanently magnetizable material exhibiting high coercive force and high retentivity and relatively longer end portions of magnetic material of high permeability disposed on opposite sides of said medial portion and in contact therewith, said short medial portion extending entirely across and completely separating said end portions; windings surrounding said core and extending lengthwise thereof beyond said medial portion on both sides thereof; a magnetic frame member secured to and extending laterally from the top end of said core and downwardly outside of said windings terminating in a lower end plate transversely positioned with respect to said core and extending across the free end of said core a predetermined distance beneath the free end of said core; said lower end plate being provided with an aperture disposed opposite the free end of said core; a movable armature having a shank portion freely movable within said aperture having a length approximating the spacing between the free end of said core and said lower end plate, the lower end of said armature being provided with a flange adapted to abut the lower margins of the aperture in said lower end plate when said armature is in closed position with the upper end of the shank portion of said armature in close proximity to the free end of said core; guiding means for said armature adapted to guide the same for free movement within the aperture in said lower end plate; stop means positioned to maintain said armature when in open position at a level such that the upper end of the shank portion of said armature is approximately flush with said lower end plate to provide a leakage path for a substantial proportion of the flux which threads said core directly between the lower end of said core and said lower end plate without passage through said armature when said armature is in open position, and opening means adapted to urge said armature to open position.

3. In an electrically controlled permanent magnet the combination comprising a central magnetic core having a relatively short medial portion composed of permanently magnetizable material exhibiting high coercive force and high retentivity and relatively longer end portions of magnetic material of high permeability disposed on opposite sides of said medial portion and in contact therewith, said short medial portion extending entirely across and completely separating said end portions; windings surrounding said core and extending lengthwise thereof beyond said medial portion on both sides thereof; a magnetic frame member secured to and extending laterally from the top end of said core and downwardly outside of said windings terminating in a lower end plate transversely positioned with respect to said core and extending across the free end of said core a predetermined distance beneath the free end of said core; said lower end plate being provided with an aperture disposed opposite the free end of said core; a movable armature having a shank portion freely movable within said aperture having a length approximating the spacing between the free end of said core and said lower end plate, the lower end of said armature being provided with a flange adapted to abut the lower margins of the aperture in said lower end plate when said armature is in closed position with the upper end of the shank portion of said armature in close proximity to the free end of said core.

ity to the free end of said core; a guiding rod for said armature extending axially through said core adapted to guide said armature for free movement within the aperture in said lower end plate; stop means positioned to maintain said armature when in open position at a level such that the upper end of the shank portion of said armature is approximately flush with said lower end plate to provide a leakage path for a substantial proportion of the flux which threads said core directly between the lower end of said core and said lower end plate without passage through said armature when said armature is in open position; an opening means adapted to urge said armature to open position.
